Attorney, Agent, or Firm—Banner, Birch, McKie and Beckett

[57] **CLAIM**

The ornamental design for a bottom of a shoe sole, as shown and described.

DESCRIPTION

FIG. 1 is a bottom plan view of a bottom of a shoe sole showing my new design;

FIG. 2 is a lateral side elevational view thereof;

FIG. 3 is a medial side elevational view thereof;

FIG. 4 is a sectional view taken along line 4—4 of FIG. 1;

FIG. 5 is a sectional view taken along line 5—5 of FIG. 1; and,

FIG. 6 is a sectional view taken along line 6—6 of FIG. 1.

The broken line showing of a shoe upper and sole periphery in FIGS. 2 and 3 is for illustrative purposes only and forms no part of the claimed design.

FIG. 2
